ELECTRIC LAMP

Hermann Krefft, Berlin-Friedrichshagen, and
 Kurt Larché, Berlin-Tempelhof, Germany, as
 signors to General Electric Company, a corpo-
 ration of New York

Application April 7, 1938, Serial No. 200,760
 In Germany April 30, 1937

7 Claims. (Cl. 176—16)

Our invention relates to electric lamps generally and to a suitable starting arrangement therefor. More particularly, our invention relates to a starting arrangement for electric lamps 5 of the high-pressure incandescent type in which a vaporizable metal contained within the lamp is vaporized during operation thereof.

It has been proposed heretofore to use as a filling for electric incandescent lamps a high-pressure metal vapor, particularly mercury vapor, in order to thereby reduce the vaporization of the lamp filament to an even greater extent than is accomplished by a rare gas filling, and in order to be able to heat the said filament to a higher 15 degree without detrimentally influencing its life. The higher temperature, of course, is coincidental with a higher light yield and higher light intensity.

It is also known that such high-pressure vapor 20 lamps, having a filament dimensioned for a high current value, cannot be connected directly to the full network voltage for several reasons. In the first place, the filament carrying such a high load will vaporize extremely rapidly when 25 the metal vapor pressure in the lamp is low, such as exists when the lamp is cold. In addition, the high voltage drop across the lamp filament tends to produce short circuits when the vapor pressure in the lamp is not sufficiently 30 high. The occurrence of such short circuits is objectionable inasmuch as they destroy the lamp. Various means have been suggested for avoiding the above-mentioned disadvantages, such as connecting a current-limiting resistance in the cur- 35 rent-supply wires and then short circuiting this resistance after the lamp has been heated up and the vapor pressure therein sufficiently high; or by first connecting several similarly designed high-pressure vapor lamps in series and later, 40 after the lamps are heated up, connecting the same in parallel to the network. In spite of the above suggestions, high-pressure vapor lamps have not as yet been introduced in practical applications because of necessary special switch- 45 ing accessories and switching procedures which make the operation of the lamp considerably more difficult.

One object of our invention is to provide a 50 high-pressure vapor lamp of the incandescent type having a starting device arranged therewith which is extremely simple in construction and which operates automatically and reliably.

Another object of our invention is to provide 55 a high-pressure vapor lamp of the incandescent

type with a suitable starting device arranged entirely within the lamp itself.

Still another object of our invention is to provide an incandescent high-pressure vapor lamp with a starting device comprising an electrical 5 resistance in series with the lamp filament and a second resistance, having a negative temperature coefficient, connected in parallel with said series resistance and adapted to automatically short circuit the said series resistance during 10 operation of the lamp.

A further object of our invention is to provide an incandescent high-pressure vapor lamp with a starting device of the above type in which the series resistance is utilized as a heating body 15 to accelerate the formation of the metallic vapor within the lamp, thereby reducing the starting time of the lamp to a considerable extent.

In the incandescent high-pressure vapor lamp according to our invention, the series resistance 20 and the resistance with the negative temperature coefficient may be advantageously arranged in the lamp base. In the case of double-walled high-pressure vapor lamps provided with an enclosing vessel, the above-mentioned resistances 25 may be placed together either within the interior of such enclosing vessel or in the lamp base, or they may be arranged separate from each other in the two spaces.

Further objects and advantages of our invention will appear from the following description 30 of a species thereof and from the accompanying drawing which is a side view, partly in section, of an incandescent high-pressure vapor lamp comprising our invention.

Referring to the drawing, the lamp there shown 35 comprises an outer enclosing bulb or envelope 1 of glass in which is mounted, preferably at the center thereof, an incandescent lamp 2 of the high-pressure metallic vapor type. The said lamp 2 consists of a small tubular bulb or envelope 2' of quartz or other hard heat-resisting glass and a coiled filament 3 mounted within said tubular envelope and disposed along the axis of the same. The filament 3 is supported within 40 the tubular envelope 2' by means of current supply wires 4, 5 sealed in opposite ends of the tubular bulb 2' and electrically connected to opposite ends of the said filament.

The incandescent lamp envelope 2' contains a 50 small quantity 6 of a vaporizable metal, such as mercury, which is preferably dimensioned in such a way that it completely vaporizes during the lamp starting period while forming the desired vapor pressure within the said bulb 2'. In other 55

words, the quantity of vaporizable metal 6 within the envelope 2' is so apportioned that during lamp operation the metallic vapor is superheated so that an unpermissible rise in the pressure of the lamp filling need not be feared even when voltage and current fluctuations occur, or when the lamp is mounted within fixtures that are closed and which dissipate the heat very slowly. The lamp envelope 2' contains, in addition to the vaporizable metal 6, a suitable gas filling, such as, for instance, a mixture of nitrogen and argon or krypton.

A base 7, consisting of a threaded metallic shell 8, insulation 9, and a bottom end contact 10, is mounted on the neck portion of the outer bulb 1, preferably by means of suitable cement 11. The current supply wire 5 is directly connected to the base shell 8 by spring contact 12, lamp support 13 and lead wire 14. The other current supply wire 4 is connected to the bottom end contact 10 through spring contact 15, lamp support 16, lead wire 17, a series resistance 18, and a lead wire 19. The said series resistance 18 consists generally of an ohmic resistance which attains a glow temperature, such as a coiled tungsten wire, and is preferably mounted closely adjacent the incandescent lamp bulb 2' for the purpose of heating it. To obtain a particularly rapid heating of the metallic filling 6 in the incandescent lamp 2, the said series resistance 18 may be arranged entirely within the incandescent lamp bulb 2', in which case the series resistance may itself form a part of the filament 3.

Mounted within the base 7 of the lamp is a resistance 20 which has a negative temperature coefficient and which is arranged to short circuit the series resistance 18, during operation of the lamp, by means of the lead 17 and a connection 21 to the lead wire 19. The resistance 20 consists preferably of low metal oxides, such as uranium dioxide or a mixture of titanium dioxide and magnesium oxide. Such resistances, in the cold state, have a relatively high electrical resistance which decreases rapidly upon heating up of the said resistance and which is negligibly small at the operating temperature. The initial heating time and the cooling time of such a resistance 20 with a negative temperature coefficient depend on the composition of the material comprising the said resistance, the thermal capacity thereof and the cooling conditions, and can be readily adapted to the rise in the vapor pressure in the incandescent lamp 2 when the same is placed in operation. In order to avoid detrimental overloads it is advisable to so design and arrange the resistance 20 with the negative temperature coefficient that when the lamp is placed in operation the said resistance 20 will not heat more rapidly than the vapor filling in the incandescent lamp 2, and when the lamp is turned off the said resistance cools at least as rapidly as the said vapor filling.

When a lamp as described above is placed in operation, the resistance value of the negative temperature coefficient resistance 20 is so large that practically the entire lamp current flows through the series resistance 18. Due to the voltage drop in the said series resistance 18, a relatively low voltage is consequently applied to the coiled filament 3. The current flowing through the filament 3 heats the same, and the heat thus radiated by the said filament results in vaporization of the metal 6 within the lamp bulb 2' to an increasing extent with a corresponding increase in the pressure of the metal-vapor fill-

ing therein. At the same time, the resistance 20 is also heated by the small current flowing through the same so that its resistance will gradually drop more and more until finally, when the operating vapor pressure of the metal-vapor filling is attained, its resistance value will have become so negligibly small that it then short circuits the series resistance 18.

Since the starting device according to our invention does not function abruptly, like mechanical switching devices, but instead functions gradually, it provides the possibility of selecting, at each instant during the lamp starting operation, the largest lamp heating current permissible in view of the vapor pressure existing in the lamp 2 at the particular moment.

By mounting the coiled tungsten wire 18, comprising the series resistance, closely adjacent the incandescent lamp bulb 2', it accordingly acts as a heating body to heat up the incandescent lamp bulb 2' during the lamp starting operation. The effect of this auxiliary heating is to accelerate the formation of the metallic vapor within the incandescent lamp 2, thereby reducing the starting time of such lamp to a considerable extent.

What we claim as new and desire to secure by Letters Patent of the United States is:

1. In combination, an electric lamp comprising an envelope, a metallic filament sealed therein, and a quantity of vaporizable metal within said envelope, and a starting device for said lamp comprising a starting resistance connected in series with said filament and a second resistance, having a negative temperature coefficient, connected in parallel with said starting resistance to thereby short circuit the latter during operation of the lamp.

2. In combination, an electric lamp comprising an envelope, a metallic filament sealed therein, and a quantity of vaporizable metal within said envelope, and a starting device for said lamp comprising a starting resistance connected in series with said filament, said starting resistance being formed as a heating body and mounted closely adjacent said envelope, and a second resistance, having a negative temperature coefficient, connected in parallel with said starting resistance to thereby short circuit the latter during operation of the lamp.

3. In combination, an electric lamp comprising an envelope, a metallic filament sealed therein and including a series resistance having a positive temperature coefficient, and a quantity of vaporizable metal within said envelope, and a starting device for said lamp comprising the said series resistance and a second resistance, having a negative temperature coefficient, connected in parallel with said series resistance to thereby short circuit the latter during operation of the lamp.

4. In combination, an electric lamp comprising an envelope, a metallic filament sealed therein, and a quantity of vaporizable metal within said envelope, and a starting device for said lamp comprising a starting resistance connected in series with said filament and a second resistance, having a negative temperature coefficient and consisting of low metal oxides, connected in parallel with said starting resistance to thereby short circuit the latter during operation of the lamp.

5. In combination, an electric lamp comprising an envelope, a metallic filament sealed therein, and a quantity of vaporizable metal within said envelope, and a starting device for said lamp

comprising a starting resistance, having a positive temperature coefficient, connected in series with said filament and a second resistance, having a negative temperature coefficient, connected 5 in parallel with said starting resistance to thereby short circuit the latter during operation of the lamp, said second resistance being so constructed and arranged as to heat up no faster than the vapor filling in said lamp when the said lamp 10 is placed in operation and to cool at least as rapidly as said vapor filling upon discontinuance of such lamp operation.

6. An electric lamp comprising an outer envelope, a high-pressure incandescent lamp mounted 15 within said outer envelope, said incandescent lamp comprising a bulb containing a metallic filament and a quantity of vaporizable metal, and a starting device arranged within said electric lamp and comprising a starting resistance connected in series with said filament and a second 20 resistance, having a negative temperature coefficient,

cient, connected in parallel with said starting resistance to thereby short circuit the latter during operation of the said high-pressure incandescent lamp.

7. An electric lamp comprising an outer envelope, a base secured thereto, a high-pressure incandescent lamp mounted within said outer envelope, said incandescent lamp comprising a bulb containing a metallic filament and a quantity of vaporizable metal, and a starting device arranged within said lamp, said starting device comprising a starting resistance mounted within 10 said outer envelope and connected in series with said filament and a second resistance, having a negative temperature coefficient, mounted within 15 in said base and connected in parallel with said starting resistance to thereby short circuit the latter during operation of the lamp.
